UNITED STATES PATENT OFFICE.

CHARLES W. CROWELL, OF SALISBURY, NORTH CAROLINA.

SUPERHEATER FOR STEAM-BOILERS.

1,159,181.

Specification of Letters Patent.

Patented Nov. 2, 1915.

Application filed October 31, 1914. Serial No. 869,646.

To all whom it may concern:

Be it known that I, CHARLES W. CROWELL, of Salisbury, in the county of Rowan, and in the State of North Carolina, have invented a certain new and useful Improvement in Superheaters for Steam-Boilers, and do hereby declare that the following is a full, clear, and exact description thereof.

My invention relates to superheaters for steam boilers, and is adapted more particularly to steam boilers of the railroad locomotive type, but as it can be used in other types of boilers, such as marine and stationary boilers, I do not restrict myself to its use only in boilers of the locomotive type.

The object of my invention is to provide a superheater that will not interfere with, or impair the boiler in any respect, will be a construction that is strong and inexpensive, easy to repair and simple so that it will obviate parts difficult and expensive to make, such as all pipes in the smoke box, except the blower and exhaust stand, large flues that are costly to make and are bad in that they leak, and the pipe coils in them and their connections, and the difficulty to make an expensive throttle box inside the boiler and which will render a steam dome unnecessary, although such may be used if desired.

More particularly I have aimed to provide a superheater especially adapted with other boiler improvements that I have made, and for which I filed applications for patent, and in particular it will be found that my present invention has matter in common with the subject of my application No. 619,051, filed April 5, 1911; and to the extent that the matter claimed herein is common to the two applications, the present application is a continuation of said application No. 619,051.

In the accompanying drawings—Figure 1 is a vertical longitudinal section, somewhat of necessity diagrammatic, of a boiler of the locomotive type embodying my invention; Fig. 2 is a vertical section on the line 2—2 of Fig. 1.

The boiler shown in the drawings has a shell 10, substantially cylindrical in form, larger at its rear end than at its front end, and having at its rear end such a fire box 11 as that of my application No. 619,051, and at its front end a smoke box 12 with a fire chamber 13 intermediate the fire box and the smoke box and composed of a cylind-

rical shell 14, and front, or flue sheets and heads 15, fire tubes 16 being extended from the flue sheet 17 at the front end of the fire box to the rear flue sheet of said chamber, 60 and fire tubes 18 being extended from the front flue sheet of said chamber to the flue sheet 19 forming the rear of the smoke box.

As the flue sheets, or heads 15 extend entirely between the boiler shell 10 from side 65 to side, and the shell 14 is eccentrically located, a crescent shaped chamber 20 is provided between the shell 14 and the boiler shell 10. Said chamber 20 constitutes the superheating chamber to which steam from 70 the steam space in the boiler is conducted by a pipe 21 leading from a high point in the boiler to the upper part of said chamber 20 where the heat from the fire chamber heats it to a high temperature. The superheated steam is taken from the superheating chamber 20, preferably at the bottom thereof, by a discharge pipe 22 having a throttle valve 23 from which pipes 24 run to the respective steam chests 25. A pipe, or pipes 80 26 (two being shown in the drawings) that are preferably coiled, or manifolded to extend back and forth between the boiler shell and the flues, are connected at their upper ends with the superheater chamber at the 85 upper side thereof and also at their lower ends at which point said pipes are each provided with a suitable valve 27 that permits superheated steam to flow from the upper part of said chamber through said pipes 26 90 where it is condensed into saturated steam and discharged into the lower part of said chamber again to regulate the temperature in said chamber, but prevents circulation through said pipes 26 when the throttle 95 valve is open. Said pipes 26 and their valves 27 may connect to the superheating chamber 20 inside, or outside the boiler for convenience in operating or repairing the valves.

When the throttle valve 23 is 100 closed, steam will enter the pipe, or pipes 26 at the upper end and circulating therethrough will condense in passing through the portions of the pipes in the colder part of the boiler and being discharged into the 105 lower side of the superheater chamber will prevent objectionable rise, or increase in the temperature of the fire chamber shell 14 when the throttle valve 23 is closed. When the throttle valve is open the valve 27 will 110 close and thus prevent saturated steam entering the discharge 22. Without the pro-

vision of means, such as the pipes 26, to pass saturated, or condensed steam into the superheater chamber when the throttle is closed, inasmuch as the fire chamber 13 continues to superheat the steam after the throttle valve is closed, the fire chamber shell 14 would become too hot. This is prevented and the temperature within the superheater chamber 20 is regulated and 5 kept down by the introduction of the saturated, or condensed steam into the same, yet when the throttle valve is open the influx of saturated steam from the regulating pipes 26 into the superheater chamber is prevented 10 and the discharge of saturated steam to the steam chest is avoided. The coils, or manifolds of the condensing pipes 26 should be close together toward the bottom of the boiler since ordinarily the water in the lower 15 part of the boiler is of the lowest temperature.

The shell 14 may be of any desired material, such as sheet copper, or steel, and stayed to the boiler by any suitable stays.

20 To connect the portions of the boiler on opposite sides of the diaphragm, or partition which the superheater's and fire chambers create, I provide water tubes 28 extending through the superheater chamber from one 25 head, or flue sheet 15 to the other. Suitable stay bolts 29 connect the shell 14 and the boiler shell 10.

A man hole 30 is provided to give access 30 to the interior of the fire chamber 13, said 35 man hole extending inward from the boiler shell 10 and outside the latter has the customary cover 31.

It is to be understood that the precise 40 form of the superheating chamber in cross section and the style of the boiler and fire box are not of primary importance, but the 45 form of the chamber and the construction of the boiler and fire box may be any that convenience of design, or other reasons may dictate or suggest.

Having thus described my invention what I claim is—

1. A fire tube boiler having in advance of the fire box, a fire chamber having a substantially round form and spaced within the 50 boiler so as to provide a steam superheating chamber between the same and the boiler wall, and flues connecting said fire chamber and the fire box.

2. A fire tube boiler having in advance of the fire box a fire chamber formed by a substantially round shell, and flue sheets at the ends of the shell that extend between the boiler walls, said shell being spaced apart 60 from the boiler shell so as to form a steam superheating chamber around the fire box, and flues extending from the fire box to one of said flue sheets, and flues extending forward from the other flue sheet.

3. A fire tube boiler having in advance of

the fire box a fire chamber that is round in cross section, flues connecting the latter and the fire box, a chamber situated between the exterior of the fire chamber and the exterior of the boiler and surrounding the fire chamber, means to conduct steam from the boiler into said chamber that is exterior to the fire chamber, and means to lead steam therefrom to the point to be used.

4. A fire tube boiler having in advance of the fire box a fire chamber, flues connecting the latter and the fire box, a chamber situated between the exterior of the fire chamber and the exterior of the boiler, means to conduct steam from the boiler into said chamber that is exterior to the fire chamber, means to lead steam therefrom to the point to be used, and a pipe in communication with said steam-receiving chamber at two points situated in the boiler so as to subject steam in the pipe to the condensing effect of water in the boiler.

5. The combination in a boiler having a fire box, a smoke box, a fire chamber that is round in cross section between said fire box and smoke box, and heating flues connected therewith, of a superheating steam chamber between said smoke box and fire box and surrounding the fire chamber, the inner wall of which separates said fire chamber from said superheating chamber.

6. The combination in a boiler of a smoke box, a fire box, a fire chamber, heating flues, a boiler shell and a steam chamber, said steam chamber being located between said smoke box, and fire box, and between said boiler shell and fire chamber, said fire chamber being formed by a shell that is round in cross section and spaced all around from the boiler shell to form a steam superheater.

7. In a boiler having heating flues, a smoke box, a fire box, a fire chamber that is round in cross section, said heating flues connected therewith, a steam chamber located between said smoke box and fire box and between said boiler shell and said fire chamber; said steam chamber having a steam pipe leading from a high point in the boiler to a high point in said steam chamber for feeding steam therein.

8. In a boiler the combination of a shell, a smoke box, a fire box, a fire chamber, heating flues connected therewith, the heads of said fire chamber extending to said boiler shell, a cylindrical shell secured to said heads of said fire chamber and spaced away from said boiler shell forming a steam chamber, the shell of said steam chamber being stayed to the boiler shell with stay bolts, and water tubes extending through said heads to convey water through the steam chamber from the front portion of the boiler to the rear.

9. A boiler having a shell round in cross section, heating flues, a fire box, a smoke box, a fire chamber located between said fire box

and smoke box and formed by a shell round in cross section, a steam chamber formed between said boiler shell and fire chamber shell, and between said smoke box and fire 5 box, said steam chamber having a throttle valve connection and steam pipes for controlling and directing steam from said steam chamber to the steam chest of the engine.

10. In a boiler having a shell, a smoke box, a fire box, a fire chamber, heating flues, a steam chamber located between said fire box and said smoke box, the inner wall of which is exposed to the heat of the fire chamber, said steam chamber having one or 15 more pipes leading from a high point in said chamber back and forth through the water space between said boiler shell and heating flues to a point in the lower part of said chamber for condensing it into saturated 20 steam and discharging it into the lower part of said chamber to regulate the temperature in said steam chamber having a valve in said pipe for controlling the current through same.

25. 11. The combination with a boiler having a fire box, a smoke box, a fire chamber between said fire box and smoke box, and heating flues connected therewith, of a superheating steam chamber between said smoke 30 box and fire box, said superheating chamber having an opening for receiving saturated steam, and an opening for discharging superheated steam from said superheating chamber and means to take superheated 35 steam from said chamber and convert it into saturated steam and to deliver it to the chamber through said saturated steam opening.

12. The combination with a boiler having 40 a fire box, a smoke box, a fire chamber between said fire box and said smoke box, heating flues connected therewith, of a superheating steam chamber between said fire box and smoke box, the inner wall of 45 which separates said fire chamber from said superheating chamber, said superheating chamber having an opening for receiving

saturated steam to reduce the temperature therein when superheated steam is not being used by the engine and means to take 50 superheated steam from said chamber and convert it into saturated steam and to deliver it to the chamber through said saturated steam opening.

13. The combination with a boiler having 55 a fire box, a smoke box, a fire chamber and heating flues connected therewith of a superheating steam chamber between said fire box and smoke box, extending around said fire chamber, said superheating chamber having one or more inlets and one or more outlets for the purpose of receiving and discharging steam and for increasing and decreasing temperature or maintaining a certain 60 temperature of steam therein. 65

14. A fire tube boiler having in advance of the fire box a fire chamber, flues connecting the latter and the fire box, a steam superheating chamber situated between the exterior of the fire chamber and the exterior of 70 the boiler, and means for taking superheated steam from said chamber at one point and delivering it as saturated steam at another point.

15. A fire tube boiler having in advance 75 of the fire box a fire chamber, flues connecting the latter and the fire box, a steam superheating chamber situated between the exterior of the fire chamber and the exterior of the boiler, means for taking superheated 80 steam from said chamber at one point and delivering it as saturated steam at another point, a throttle controlling the discharge of steam from said chamber, and automatic means to control the delivery of saturated 85 steam to the superheated steam chamber according to the condition of the throttle.

In testimony that I claim the foregoing I have hereunto set my hand.

CHARLES W. CROWELL.
